STRIPE PAINTING MACHINE

Herbert T. Morgan, Santa Barbara, Calif.

Application February 14, 1934, Serial No. 711,260

14 Claims. (Cl. 91—62.6)

This application is a continuation in part of my prior copending application Serial No. 506,800, filed January 5, 1931.

The present invention relates to improvements in stripe painting devices and has for an object to provide an improved device for painting lines or stripes on automobiles, signs, furniture, etc.

The invention is intended to replace the present method of painting lines, stripings and the like on automobiles, furniture, signs, interior decorations and the like, such as stripings on cupboard doors, cabinets, etc. The present method requires the labor of highly skilled mechanics who must use a fine brush with painstaking care, which necessarily makes the work slow and expensive.

The improved device consists of an automatic, self-feeding painting device, which may or may not be mounted upon a specially designed adjustable carriage with an adjustable holder for guiding the paint brush on a given line.

Another object of the invention is to provide an improved painting device or brush which will be automatic in action in the manner of feeding the paint to the brush tip whereby to insure a free flow of the paint and the uniform making of the objects.

A further object of the invention is to provide an improved painting or striping device useful in connection with a carriage which will be guided by a molding, or which may carry a gage or guiding device for the purpose of compelling the striping to follow a straight line.

A still further object of the invention is to provide an improved painting or striping device in which an automatic vibrator may be provided in connection with the paint feeding tongue which operates through the paint discharge tip for the purpose of facilitating the continuous and uniform feed of the paint to the object surface.

A still further object of the invention is to provide a reservoir in connection with the device so arranged and mounted that it may always occupy a substantially vertical position the better to induce the flow by gravity of the liquid paint therefrom.

The invention is also concerned with certain auxiliary devices, such as guiding tracks for the carriage, a tiltable table support for the brush or pencil, and nozzles or tips of various sizes and shapes for the production of fine or heavy lines in single or multiple groups.

With the foregoing and other objects in view, the invention will be more particularly described

hereinafter and more fully pointed out in the appended claims.

In the drawings, in which like reference characters denote like parts throughout the several views,

Fig. 1 is a side elevation of an improved painting device constructed in accordance with the present invention.

Fig. 2 is a vertical section taken on an enlarged scale through the device at substantially right angles to Fig. 1.

Fig. 3 is a top plan view of the device with parts broken away and parts shown in section.

Fig. 4 is a side view of the device apart from the carriage and showing the method for painting or striping perpendicular surfaces.

Fig. 5 is a side view of a modified form of the invention for use without the carriage.

Fig. 6 is a vertical section taken on the line 6—6 of Fig. 7 and showing a duplex form of brush tip.

Fig. 7 is a similar view taken on the line 7—7 in Fig. 6.

Fig. 8 is a top plan view of a form of track used as a guide for the carriage.

Fig. 9 is a cross section on the line 9—9 of Fig. 8.

Fig. 10 is a view in elevation of a modified form of the invention with parts broken away and parts shown in section.

Fig. 11 is a fragmentary cross section taken through the central part of the carriage on the line 11—11 in Fig. 3.

Fig. 12 is an elevation, partly in section, of an alternative structural embodiment of the invention.

Fig. 13 is an elevation, partly in section, illustrating an adaptation of the invention wherein an electric vibrator is used in connection with the structural embodiment as shown in Fig. 12.

Fig. 14 is a section taken on the line 14—14 of Fig. 13.

Fig. 15 is a longitudinal section taken through a further alternative embodiment of the invention and illustrating in detail the manner of assembling the paint feeding stem.

Now it will be understood that the device is susceptible of many mechanical forms, some few only of which are illustrated in the drawings. Referring more particularly to the drawings, 12 designates a tip having an outlet orifice for directing the paint on to the surface to be striped. Through the orifice of the tip 12 a paint feeding tongue 13 is adapted to project. This tongue 13 will normally be projected by resilient spring 55

action outwardly of the tip 12, but will be shifted inwardly of the tip 12 when such tip engages the surface to be painted as shown in Fig. 2.

Now the tip 12 may be made in various shapes 5 and sizes with one or more orifices of various dimensions and for this purpose the tips are preferably interchangeable. To this end the tips may be provided with internally threaded sockets 14 for screwing on and off externally threaded nipples 15 upon a tubular nipple holder 16. The holder 16 is provided with a nut portion 17 for enabling it to be screwed into and out of a tubular reservoir barrel 18. The nipple holder 16 carries therewithin an automatic valve device 15 similar to the valve insides of the inner tube of an automobile tire. The stem 19, which carries the tongue 13 extends up through the holder 16 and the valve insides. When the automatic valve is open, as it is shown in Fig. 2, the paint is adapted 20 to feed along the stem 19 down to the tongue 13 and out on to the surface with which the tip 12 is in contact.

Although the valve insides is well known in construction and operation it will be briefly 25 described as follows:

A hollow threaded cap 20 is screwed into the lower end of the holder 16 and carries the valve seat 21 which fits snugly within the holder, this valve seat 21 being usually provided with an 30 outer part of rubber. Both the parts 20 and 21 have a loose fit about the stem 19. Affixed so as to move with the stem 19 is a valve plunger 22 having a valve facing to seat against the seat 21, the valve being urged against the seat 21 by a coiled spring 23 which is wound about the stem 19 and abuts at one end against the plunger 22 and at its other end against a collar 24 loosely fitting about the stem 19 and abutting against a shoulder 25 within the holder 16. 40 In Fig. 2 the valve 22 is shown as being open or raised from its seat 21 owing to the fact that the tongue 13 has been pushed inwardly by contact with the surface to be painted.

Although an automatic vibrator is not essential, when such device is to be used, the stem 19 is continued upwardly and engages in a socket 26 formed in an armature 27 of an electrical vibrating or other vibrator device. The coil of the vibrator is indicated at 28 and the make and 45 break contact at 29. The lead in wires 30 may carry a plug for connection to any electrical outlet socket. When the current is turned on, the energized core 31 of the electromagnet 28 will attract the armature 27, thus breaking the 50 circuit at the contact 29 which will destroy the attraction, thus allowing the contact to spring back and make the circuit again at 29. This make and break action continues rapidly in the 55 vibration of the stem 19 and the tongue 13, and 60 inducing the free flow of the paint to the painted surface through the nozzle 12.

The vibrating device is shown as contained within a holder 32 forming a unitary device which may be screwed into and out of or otherwise 65 removably connected with a base 33. Through a coupling device 34, the base 33 may be carried upon a metal or other hollow tube 35 which will surround and protect the stem 19. The tube 35 may be supported in any appropriate 70 manner in axial alignment with the barrel 18. Where a supply reservoir, such as the reservoir 36 is to be used in conjunction with the painting device, it will be appropriate to join the tube 35 and the reservoir connection in the 75 same coupling member. To this end a T-cou-

pling is shown into the lower branch of which the barrel 18 is screwed and to the upper branch of which the tube 35 is connected as by the use of a coupling sleeve 38. Within this coupling member may be mounted a tubular rubber or 5 other sleeve or gasket 39 which will have a tendency to prevent any of the paint from flowing upwardly into the tube 35. The horizontal branch of the T-coupling 37 is connected to a needle valve casing 40. Within the casing 40 10 is a needle valve 41 operable by a head 42 for the purpose of controlling the outflow from the reservoir 36 to the brush. The reservoir 36 preferably has a swivel mounting about the needle valve casing 40. This swivel support is had by 15 means of a sleeve 43 carrying the reservoir 36 and fitting rotatably about a reduced portion or neck 44 of the needle valve casing 40. The sleeve 43 abuts at one end against a shoulder 45 formed by the enlarged portion of the needle 20 valve casing 40 and a friction washer 46 is preferably interposed between these parts. At its opposite end the sleeve 43 is confined by a nut 25 threaded upon the reduced neck 44 and having a friction washer 48 interposed between the nut 47 and the sleeve 43. By loosening the nut 47, the sleeve 43 and reservoir 36 may be adjusted angularly to any desired position about the needle valve casing 40. Upon tightening the nut 47, sufficient frictional pressure may be brought to 30 bear to retain the reservoir 36 in the adjusted position. An annular channel 48' of the sleeve 43 circumscribes a circumferential group of ports 49 in the reduced neck 44. The needle valve 41 35 may be carried by a screw sleeve 50 which will permit the valve assembly to be removed for purposes of cleaning.

The reservoir 36 is preferably removably carried by the swivel sleeve 43 and carries a downwardly projecting threaded socket 51 to receive 40 the threaded nipple 52 of said sleeve. The reservoir 36 may be of any appropriate construction, one form of which is shown in Fig. 2, as comprising an external receptacle with an internal tube 53 therein. This internal central 45 tube 53 is important when the device is used in the manner illustrated in Fig. 10. The reservoir 36 may be filled with fluid paint by removing the cover 54 provided with the breathing opening 55. Outflow of the paint is under the control of a valve 56 which is threaded through the side of the reservoir and through an orifice in the side wall of the tube 53. By opening the valve 56 the paint will be permitted to flow through the orifice down to the needle valve 41. 55

A supply of the paint may always be kept in the tube 53 to flow out under control of the needle valve 41. An extremely fine adjustment may be had by this needle valve 41. Into the upper end of the tube 53 is screwed a coupling 57 which 60 projects up through the cap 54 and receives a small cap 58 serving to close the upper end thereof when used in the manner shown in Fig. 2. When used in the manner illustrated in Fig. 10, this small cap 58 may be removed to permit 65 the coupling 57 to be screwed directly into the socket 59 projecting downwardly from the vibrator base 33.

Whereas in Fig. 2 the vibrator 32 is shown to be in line with the tip and the vibrating tongue, 70 and the reservoir 36 is shown to one side of these parts, in Fig. 10 the reservoir 36 and vibrator 32 are illustrated as in line with one another and with the tip and vibrating tongue. In this instance, the vibrating stem 19 extends up through 75

the tube 53 of the reservoir and up into the vibrator which is coupled to the reservoir in the manner just related. In Fig. 10 the needle valve 41 is dispensed with and a closure cap 60 is fitted over the horizontal branch of the T-coupling 37. The device in Fig. 10 may be used in substantially the same manner as a pencil, being guided across the surface to be painted or striped by the hand of the operator. Of course, the vibrating device 32 might be omitted from Fig. 10, and the vibration of the tongue 13 may be obtained by maintaining a steady pressure of the tip 12 against the surface to be painted and drawing the tip 12 along this surface. This action causes tongue 13, which is depressed and under tension, to skip along over the infinitesimal bumps and hollows which will be found even on the smoothest piece of glass.

Another embodiment of the invention, illustrated in Fig. 5, shows the reservoir 36 dispensed with, a supply of the liquid paint being maintained in a barrel 62 which forms the pencil or enclosing casing of the device. This enclosing casing 62 is in effect a large barrel, or rather an enlargement of a barrel, such as the barrel 18 shown in Fig. 2. The valve assembly, tip and tongue arrangement shown in Fig. 2 and already described is carried by this barrel 62. The barrel 62 may receive a supply of liquid paint through the filling neck 63 which is normally closed by the cap 64. The barrel 62 may or may not carry the vibrator 32.

In Figs. 6 and 7 I show a modified form of the tip 12' and the tongue arrangement. In this instance the tongue is provided with two forks 13' adapted to operate through two orifices in the tip 12'. This is for the purpose of making two parallel lines or markings. It will be quite apparent that the tongues may be made in any multiple number of forks with orifices to correspond in the tip. The tongues may also be made of various widths for making heavy and light lines.

Referring more particularly to Fig. 4, the device described in connection with Fig. 2 is shown as for use in making vertical markings upon a perpendicular surface. Here the value of the swivel connection for the reservoir 36 is apparent. Whereas the pencil or brush device is obliged to assume a substantially horizontal position for the purpose of making these perpendicular markings, nevertheless, the reservoir 36 may be shifted to an upright position whereby the flow of the paint under the force of gravity may be maintained just as in the case where horizontal surfaces are being marked or striped.

Referring more particularly to Figs. 1, 2 and 3, the brush or pencil is also adapted for mounting in connection with a carriage including a pair of relatively movable trucks 65 and 66 supported for rolling movement upon wheels 67 and 68. These wheels are slidably mounted on axles 69 and 70. The trucks and their respective wheels are secured to the axles 69 and 70 by the use of set screws 71 and 72. Upon the trucks 65 and 66 is an adjustable bed 73 slotted, as indicated at 74, to receive set screws 75 which take into the trucks. By loosening the set screws 75 and the set screws 71 and 72, the trucks 65 and 66 may be adjusted axially along the axles 69 and 70 and the bed 73 may be adjusted relatively to the trucks 65 and 66.

A plate 76 is mounted upon the bed 73 and above such plate 76 is a tiltable platform 77 having screws 78 in any appropriate number threaded

therethrough and taking against the plate 76. Through both plate 76 and the platform 77 and also through the bed 73 extends a pivot bolt 79 (Fig. 2) having a head 80 at its lower end for engaging beneath the bed 73 and enabling the 5 tiltable platform 77 to be rotated on the bed. Riveted or otherwise secured to the tiltable platform 77 is a plate 81 having a bracket 82 rising therefrom and swivelly connected with an 10 standing curved arm 83 on a holding sleeve 84 10 adapted to embrace the barrel 18 of the pencil or brush. A set screw 85 carried by the sleeve 84 15 clamps against the barrel 18. By unloosening the screw 85, the barrel 18 and the entire pencil or brush may be rotated in the sleeve 84 for purpose 15 of adjustment. The lower part of the arm 83 20 swivelly carries a rod 86 which extends through the bracket 82 and is surrounded by a coil spring 87, the tension of which may be adjusted by a nut 88 threaded upon the outer end of the 20 rod 86. As shown in Fig. 3, a wing nut 89 may be employed to make fast the swivel connection 25 between the bracket 82 and the arm 83.

As shown in Figs. 2 and 3, a gage plate or guide 90 may be mounted upon the axles 69 and 70. Bearings 91 which slip over the axles carry the plate 90, and set screws 92 are provided for fixing the bearings upon the axles in the appropriate position. As shown in Fig. 2, this gage plate or guide 90 may operate against a side 30 surface of the surface to be painted or striped and thus cause the carriage and the pencil to move in a rectilinear path which is essential in making an accurate straight line or in a true curved line, or the carriage might be guided by 35 a track such as shown in Figs. 8 and 9, in which a track strip 93 is shown being connected by pieces 94 to rubber or other vacuum cups 95. These vacuum cups 95 are pressed tightly against the surface to be painted or striped and the 40 wheels of the trucks are rolled along against the guide strip or track 93 thus insuring the correct path for the pencil tip.

In the use of the device, a simple form of the 45 implement will consist merely of the tip, vibrating tongue, and valve device with an appropriate source of paint supply. This device may be moved over the surface to be painted guided by the hand of the operator. During this movement the tip will be vibrated toward and from 50 the surface thus giving the necessary vibration to the tongue to open the valve 22 and permit the free flow of the paint, or the vibrating device may be included, as shown in Fig. 5. Where both the vibrating device and the reservoir are 55 desirable, either the form shown in Fig. 2 or that shown in Fig. 10 may be employed.

The device may also be mounted upon the carriage with or without the gage 90 or the guide strip 93. Where there is a molding to be followed such as is found upon automobiles, the trucks 65 and 66 of the carriage may be grouped closely together so that the wheels 67 and 68 will engage opposite sides of such molding. Here the molding itself is the guiding surface or track. 60 It will be obvious that the pencil may be placed between the trucks 65 and 66 or the trucks may be grouped together and the pencil disposed at one or the other side of the trucks. In encountering irregular or sloping surfaces, the tiltable platform 77 may be caused to assume any angular position by adjusting the set screws 78. Also this platform 77 may be rotated to a desired position about the central bolt 79. A nut 79' may be used to tighten bolt 79. The coil spring 87 70 75

will add the requisite pressure of the tip against the surface to be painted. In operating the device, the heel of the hand may be placed upon the carriage while the pencil is taken between the thumb and fingers as in the act of writing with a lead pencil. This will facilitate the movement of the carriage and the proper operation of the device.

From the construction it will be apparent that the tip may be readily removed and interchanged for tips of other sizes and forms. The tips may be readily removed for cleaning as may other parts of the device. The paint may be supplied to the barrel or reservoir of the device by the use of a pump or syringe.

In the structural embodiment shown in Fig. 12, the tubular reservoir 36' is provided with a lateral rectangular enlargement providing a reservoir 36'' whereby the capacity of the reservoir is increased. The reservoir has an extension 51' that is disposed in swivel connection with the axially aligned barrel section 18' which in turn is connected at its outer extremity, as by threading, with a holder 16' which receives in detachable engagement the threaded tip 12' provided with an axial paint feed bore and having therein a valve seat which is adapted to be closed by a valve 24' disposed on the stem 19' which extends axially through the tip, the holder, and through the barrel 18'. The inner extremity of the stem 19' lies well within the reservoir 36' and is provided at its end with an eye which receives in sliding engagement the second stem 19'' having its outer end provided with an eye 98 that is slidably engaged over the stem section 19', which eye acts as an abutment for a coiled expansion spring 97 surrounding the stem section 19' between the eye 98 and a fixed enlargement 96 carried by the stem section 19' and within the barrel 18'.

The reservoir 36' is further provided with a tubular extension 99 axially aligned with the extension 51' at the opposite end of the reservoir, which extension 99 receives in threaded engagement a filler plug 100 provided on its inner face with an inwardly extending tubular socket 101 that is adapted for loose sliding engagement over the extremity of the stem section 19''. The socket 101 is internally threaded to receive the threaded stem 102 of a tensioning screw 103 threaded in the socket and which is adapted to be adjusted so that its inner end bears against the tip of the stem section 19'' within the socket and forces the same inwardly of the reservoir against expansion of the spring 97 which, in turn, acting against the shoulder 96 imparts a tension to the stem section 19''. This arrangement of elements allows an extremely fine extension adjustment of the projecting stem 19' at the tip 12'.

It is to be noted furthermore that the swivel connection of the reservoir with the barrel 18' permits of a vertical disposition of the reservoir section 36'' irrespective of vertical or horizontal use of the stripper tip 12'. The barrel section 18' has slidably disposed thereover a longitudinally extending sleeve 104 that is adapted to be fixed in a desired position by manipulation of a set screw 105 and which sleeve carries two parallel spaced laterally extending threaded stems 106, each of which has threaded thereover a pair of retaining nuts 107 which are adapted to receive therebetween the shank 108 of a work guide element. The shank 108 may comprise a substantially flat bar apertured for engagement over the

stems 106 and which is provided at its end toward the tip of the stripper with a stem 109 which is longitudinally slideable in one end of a tubular casing 110, with the extremity of the stem 109 bearing against a compression spring 111 seated within the casing. The casing at its outer extremity carries a work engageable guide wheel 112. Obviously, by proper adjustment of shank 108 by the adjusting nuts 107, the guide element may be properly disposed in parallel spaced relation to the work engaging tip 12' of the stripper.

Figure 13 illustrates an adaptation of the stripper as shown in Fig. 12 wherein an electric vibrator is employed, the details whereof are substantially similar to the vibrator shown in Figs. 1, 2 and 10.

In the embodiment shown in Figure 13, like reference characters have been employed to designate like parts as in Fig. 12. In this embodiment of the invention the casing 32' of the vibrator unit is attached directly to the reservoir extension 36''. The vibrator comprises an electrical coil 28' having a magnetic core 31' adapted to cooperate with the make and break contact 29' to cause oscillation of a striker arm 27' that projects from the casing 32' and which is provided with a down turned portion 27'' which is received within the reservoir 36'' through a slot provided for the purpose to permit sufficient oscillation of the striker arm in operation of the vibrator. At its lower end the striker arm 27' is forked for straddling in loose engagement over the stem section 19''.

It will be apparent that as the vibrator is operated the rapidly oscillating striker arm 27' through its loose forked engagement over the stem section 19'' will alternately strike the stem section from opposite sides and thus impart thereto a vibration which is in turn transmitted to the stem section 19' at the tip of the stripper. Thus, the vibration is secured without imparting any movement to the stem axially of the tip 12'. This is an important feature of the invention in that the necessary vibration is imparted to the stem to assure a constant feed of the paint material and yet at the same time there is no actual reciprocation of the stem within the tip 12' during this vibration. In the art of vibrators employed prior to the advent of this invention there has been in every instance a reciprocatory movement of the stem or tongue axially of the tip and this results in a rapid striking of the work with a consequent tendency to disalignment. In the present invention the stem 19' is depressible within the tip upon work contact and thereafter does not move axially of the tip until the stripper is released from contact with the work.

In the special embodiment shown in Fig. 15 there is an axial alignment of tip 12', holder 16', and paint reservoir barrel 113. This structure as to stem arrangement and general disposition of parts is practically identical with the form shown in Fig. 12, except that the reservoir extension 36'' of that figure is eliminated in this form. Like parts have been indicated by like reference characters so that no further description for these elements is necessary.

In the structural embodiment as shown in Fig. 15, the work guide element may be mounted directly on the barrel 113 through the instrumentality of sleeve 114, adjustable along the barrel by a set screw 115, and which sleeve carries a projecting threaded stem 116 which receives the shank 117 of the guide element, adjustment being secured by proper manipulation of the ad-

justing nuts 118. The shank 117 is longitudinally slotted as at 119 to provide for a proper sliding engagement thereof with respect to a retaining stem 120 formed on the barrel as the sleeve is adjusted over the barrel.

5 What I claim is:

1. A paint striping device comprising a holder, a tip carried thereby, a resiliently seated valve in said holder, a vibratory tongue in said tip, a stem connected to said tongue and to said valve, a tube above the holder, an electric vibrator mounted above said tube and connected to said stem, a coupling member uniting said holder and tube, an adjustable valve in said coupling member, and a reservoir for paint swivelly carried by said coupling member.

10 2. A paint striping device comprising a brush, a carriage, a swingable and reversably tiltable platform on the carriage for supporting the brush, means for tilting said platform and spring means for arcuately swinging the brush yieldably into contact with the surface to be painted.

15 3. A paint striping device comprising a brush, a carriage including axles, wheeled trucks adjustably mounted on said axles, a bed adjustably carried by said trucks, a rotary and tiltable platform carried by said bed, means for tilting said platform, and means whereby the brush is carried by said platform.

20 30 4. A paint striping device comprising a tip, a holder for the tip, a vibratory tongue in said tip, a stem connected to said tongue, a tube above the holder, a coupling member uniting said tube and holder, an electric vibrator mounted above said tube and connected to said stem, a reservoir for paint carried by said coupling member adjacent said tube, said reservoir having a height less than the length of said tube, a second tube corresponding in dimensions to said first tube 35 axially carried by said reservoir and extending therethrough, coupling means at the ends of said second named tube and valvular means for regulating the flow of paint from the reservoir to said second named tube.

40 45 5. A paint striping device comprising a holder, a tip carried thereby, a valve in said holder, a vibratory tongue in said tip, a stem connected to said tongue and to said valve, a tube above the holder, a vibrator mounted above said tube and connected to said stem, a coupling member uniting said holder and tube, an adjustable valve in said coupling member, and a reservoir for paint carried by said coupling member.

55 6. A paint striping device comprising a work contacting tip, a spring projected tongue carried thereby and depressible thereinto by work contact, means for dispensing paint through said tip, and means for imparting lateral vibration only to said tongue.

60 7. A paint striping device comprising a work contacting tip, a spring projected tongue carried

thereby and depressible thereinto by work contact, a holder for said tip, a stem connected to said tongue and extending through said holder, means for dispensing paint through said tip, and a vibrator unit detachably engageable over said holder and stem in a manner to vibrate said stem and tongue without movement thereof axially of the tip.

5 10 8. A paint striping device comprising a work contacting tip, means for dispensing paint therethrough, a valve in said tip and biased to closed position, means for automatically opening said valve on contact of the tip with work, a stem on said valve, and means for imparting lateral vibration only to said stem.

15 9. A paint striping device comprising a work contacting tip, a holder for said tip, a reservoir associated with said holder, a spring projected tongue extending through said tip, holder and reservoir, and manually operable means in said reservoir for adjusting the spring projected tension of said stem, and said means being operable externally of the reservoir.

20 25 10. A paint striping device comprising a work contacting tip, a spring projected tongue carried thereby and depressible thereinto by work contact, a holder for said tip, a stem forming part of said tongue and extending through said holder, means for dispensing paint through said tip, and means for alternately striking said stem from opposite sides to impart vibration thereto without moving the same axially of the tip.

30 35 11. A paint striping device comprising a work contacting tip, means for dispensing paint therethrough, a valve in said tip and biased to closed position, means for automatically opening said valve on contact of the tip with work, a stem on said valve, and means for striking said stem laterally thereof for imparting vibration thereto.

40 45 12. A paint striping device comprising a tip, a holder for the tip, a reservoir associated with said holder, a stem disposed through said tip, holder and reservoir, and means carried by said reservoir for imparting lateral vibration only to said stem.

50 55 13. A paint striping device comprising a work contacting tip, a holder therefor, a reservoir associated with said holder, a spring projected tongue extending through said tip and holder, a tension adjusting element extending through said reservoir in slidale engagement with said spring projected tongue, and means externally of the reservoir for operating said tension adjusting element.

60 65 14. A paint striping device comprising a tip, a tip holder portion, a reservoir associated therewith, a stem disposed through said tip, holder and reservoir, and a stem striking vibrator in said reservoir and operable laterally of the stem within the confines of the reservoir.

HERBERT T. MORGAN.
